E. M. WHITE,
VALVE MECHANISM,
APPLICATION FILED FEB. 20, 1912.

1,189,894.

Patented July 4, 1916.

UNITED STATES PATENT OFFICE.

ERNEST M. WHITE, OF GLOBE, ARIZONA, ASSIGNOR TO PACKARD MOTOR CAR COMPANY,
OF DETROIT, MICHIGAN.

VALVE MECHANISM.

1,189,894.

Specification of Letters Patent.

Patented July 4, 1916.

Application filed February 20, 1912. Serial No. 678,852.

To all whom it may concern:

Be it known that I, ERNEST M. WHITE, a citizen of the United States, and a resident of Globe, Arizona, have invented certain Improvements in Valve Mechanism, of which the following is a specification.

One object of my invention is to provide a novel form of valve mechanism particularly adapted for use in connection with multi-cylinder internal combustion engines, whose construction and arrangement of parts shall be such as to cause the valves to wear evenly, the lubricant to be suitably distributed and the distortion of the cylinder structure from unequal expansion to be reduced to a minimum.

I further desire to provide a novel form of valve mechanism for internal combustion engines which shall be relatively inexpensive to manufacture, and of such construction that there shall be no side pressure on the valves due to the thrust of gears or the pull of a chain and in which the valves need not necessarily be in line with each other.

I also desire to provide rotary valve mechanism for multi-cylinder internal combustion engines which shall be so arranged, and of such construction that if one or a pair of the cylinders becomes damaged it may be replaced with the utmost convenience; the construction being such as to permit the various pairs of cylinders being cast separately.

These objects and other advantageous ends I secure as hereinafter set forth, reference being had to the accompanying drawings, in which;—

Figure 1 is a horizontal section on the line *a—a*, Fig. 2 of a multi-cylinder engine equipped with my invention; Fig. 2 is a vertical section taken through the center line of the valves Fig. 1; and Fig. 3 is a vertical section on the line *b—b* Fig. 1.

In the above drawings I have shown the engine as constructed with four cylinders 1, 2, 3 and 4 of which there are two in each of two cylinder castings 5 and 6. Each cylinder has at its upper end two ports 7 and 8, of which the first in each instance opens into an elongated cylindrical cavity extending

horizontally through the two castings 5 and 6. Said cavity has opposite each cylinder an upwardly extending inlet port 9 and a downwardly extending exhaust port 10, there being rotatably mounted in said cavity 55 adjacent each of the ports 7 an enlarged rotary valve. A spark plug or other suitable charge igniting device (not shown) is mounted in each of the ports or openings 8. These four valves, indicated at 11, 12, 13 60 and 14, are respectively connected together by some form of universal joint; those between the valves 11 and 12, and 13 and 14 consisting of relatively short cylindrical pieces 15 and 16 each connected to its associated valves by two pivot pins 17 and 18 which extend in lines substantially at right angles to each other.

As shown in the drawings the pieces 15 and 16, as well as two other coupling pieces 19 70 and 20, extend loosely into suitable cavities of their valves, so that they are free to move laterally to a limited extent on their pivot pins.

The coupling piece 20 connects the two 75 valves 12 and 13, to which it is attached by pins 17 and 18 respectively and is of greater length than the pieces 15 and 16 in view of the greater distances between the two cylinders 2 and 3. Obviously, however, all of 80 the connecting pieces may be of the same length, or of different lengths without departing from my invention.

The valve 11 is connected by the coupling piece 19 to the enlarged end 21 of a driving 85 shaft 22, which is provided with a squared portion 23 for the reception of a sprocket wheel 24, or other driving means as desired. The squared part of said shaft is free to slide longitudinally through this driving 90 wheel and is preferably inclosed in a casing 25, which has a bearing for a rotary member 26 connected in any suitable manner to a driving wheel 27, in the present instance shown as in the form of a flanged pulley. 95 That end of the shaft 22 which extends into the rotary structure 26 is provided with a projecting pin 28 fitting into a recess 29 formed in said rotary structure 26. A plate 30 is mounted between said structure and 100

the sprocket wheel 24, and is flanged adjacent the shaft 22 so as to coöperate with the pin engaging part of the rotary member 26 in providing means whereby as the wheel 27 is turned, a longitudinal reciprocating movement is given to the shaft 22 through the medium of its pin 28 and hence to the four valves connected to it. These two structures 26 and 30 therefore form a cam for moving the shaft 22 independently of, and out of time with the sprocket 24 which rotates the various valves; the wheel 27 being driven from some rotating part of the engine, capable of attaining this end. Under operating conditions therefore, the sprocket wheel 24 is turned through a chain 33 from a sprocket wheel 34, which in turn is driven through a chain 35 from a sprocket wheel 36 on the main shaft of the engine.

As before noted, the wheel 27 is driven at any suitable speed from some part not in time with the sprocket wheel 24, so that by reason of the action of the cam on the pin 28, the shaft 22, and with it all four of the valves, are longitudinally reciprocated in such a manner that a given point on one of said valves seldom contacts with another given point on the walls of the valve cavity except at relatively long intervals of time. As a consequence the lubricant, which may be supplied to the valves in any desired manner, is very uniformly spread over their entire surface and there is no opportunity for said valves to wear in rings or otherwise unevenly. Moreover by reason of the fact that the valves are connected together and to their driving shafts by universal joints, they do not bend or cut by reason of any distortion which might occur owing to the unequal contraction or expansion of the cylinder structures under operating conditions. It is not necessary that the elongated cylindrical cavity for the various valves be made with such accuracy as is necessary if the valves are rigidly connected, for said valves can operate satisfactorily even if they are slightly out of line, and under conditions of use, there is no side pull or pressure on any of the valves from the driving chain 33. The wheel 27 is driven through a belt 38, passing over a pulley on the intermediate shaft 39 of different diameter from the sprocket wheel 34 which drives the chain 33, so that the reciprocation of the valves is not in time with their rotation. The various valves 11, 12, 13, 14 may be made of any suitable design although in the present instance I have shown them as cylindrical in form and each provided with transverse recesses 11^a, 12^a, 13^a and 14^a as the case may be placed to alternately connect the cylinder ports with the inlet and exhaust ports.

As understood by those skilled in the art,

the rotation of the various valves successively admits fuel to the various cylinders through ports 9 and 7, and thereafter permits escape of the gases of combustion through the ports 7 and 10.

I claim:

1. The combination in an engine of a cylinder; a piston within the cylinder; a valve chamber; a valve therein; means for rotating the valve in time with the movement of the piston; and independent means for longitudinally moving the valve out of time with its rotary movement to prevent any point on said valve contacting with a given point on the wall of the valve chamber except at relatively long intervals.

2. The combination in an engine having a plurality of cylinders, of a piston for each cylinder; a series of valves for said cylinders; means for rotating the valves in time with the pistons of their respective cylinders; and other means for longitudinally reciprocating the valves at a rate out of time with their rotary movements.

3. The combination in an engine of a series of cylinders; pistons therefor; a series of valves for the cylinders; relatively loose connections formed to permit universal movement between the various valves; means for rotating the valves; and means for reciprocating the valves.

4. The combination in an engine of a series of cylinders; pistons therefor; valves for said cylinders; a driving member for rotating the valves; a cam for longitudinally moving the valves out of time with said driving member; and independent means for respectively operating the cam and the driving member.

5. The combination in an engine of a series of cylinders having ports and provided with an elongated cylindrical cavity communicating therewith; valves in said cavity respectively adjacent the ports of the cylinders; universal joints between the valves; a driving shaft; universal joints between one valve and said shaft; a driving member slidably mounted on the shaft rotatably connected thereto; a cam operative on the shaft for longitudinally moving the same; and means for actuating the cam, the parts being proportioned to cause the longitudinal movement of the valves to be out of time with their rotary movement.

6. In a hydrocarbon motor, the combination with the motor base and separated cylinder blocks mounted thereon, of a rotary valve in each of said cylinder blocks for controlling ports therein, and a universal coupling between said valves whereby one may be driven by the other.

7. In a hydrocarbon motor, the combination with the motor base and separated cylinder blocks mounted thereon, of a horizon-

tal rotary valve in each of said cylinder blocks for controlling ports therein, and a universal coupling between said valves whereby one may be driven by the other, 5 said coupling being mounted in the ends of the valves independently of the cylinder blocks.

In testimony whereof, I have signed my name to this specification, in the presence of two subscribing witnesses.

ERNEST M. WHITE.

Correction in Letters Patent No. 1,189,894.

It is hereby certified that in Letters Patent No. 1,189,894, granted July 4, 1916, upon the application of Ernest M. White, of Globe, Arizona, for an improvement in "Valve Mechanism," an error appears in the printed specification requiring correction as follows: Page 1, line 56, for the word "enlarged" read *elongated*; and that the said Letters Patent should be read with this correction therein that the same may conform to the record of the case in the Patent Office.

Signed and sealed this 25th day of July, A. D., 1916.

[SEAL.]

F. W. H. CLAY,

Acting Commissioner of Patents.

Cl. 121—24.
